UNITED STATES PATENT OFFICE.

ROBERT D. BAKER, OF DETROIT, MICHIGAN.

PAVING APPARATUS.

1,390,479.

Specification of Letters Patent. Patented Sept. 13, 1921.

Application filed April 6, 1914. Serial No. 830,001.

To all whom it may concern:

Be it known that I, ROBERT D. BAKER, a citizen of the United States of America, residing at Detroit, in the county of Wayne and State of Michigan, have invented certain new and useful Improvements in Paving Apparatus, of which the following is a specification, reference being had therein to the accompanying drawings.

10 My invention relates to paving apparatus and more particularly to an apparatus designed to be employed in the forming of concrete or like paving. The invention has among the objects thereof to provide a device by which the leveling of the face or top surface of the paving may be easily and properly accomplished; to provide a structure which will properly finish or surface the face of the pavement; to provide 15 a device by which the leveling and the surfacing of the pavement may be accomplished in a single operation; and further to provide a pavement-surfacing apparatus that may be readily adapted to pavements of 20 various crowns. Other objects of the invention will more fully hereinafter appear.

The invention resides in the novel construction, arrangement and combinations of the various parts as hereinafter set forth 25 and as particularly pointed out in the claims.

In the drawings,—

Figure 1 is a top plan view of the device embodying the invention;

30 Fig. 2 is a side elevation on a reduced scale, showing the apparatus in operative relation to a road;

Fig. 3 is an enlarged end elevation;

35 Figs. 4 and 5 are enlarged sections on the lines $x-x$ and $y-y$ respectively of Fig. 1;

Figs. 6 and 7 illustrate the adjustability of the surfacing members; and

40 Figs. 8 and 9 show certain details of construction.

In the laying of paving formed from concrete or like material, it is necessary to properly level the concrete so as to give the pavement the desired crown, and also it is very desirable to surface or properly finish the pavement so that the latter will be smooth. With the methods now in general use, the concrete—after it has been poured upon the bed—is leveled and crowned by means of 45 a comparatively narrow striker bar extending from side to side of the road and having the bottom face thereof shaped to give the proper crown to the pavement. This striker bar is actuated by hand, and after it has been drawn across the face of the pavement, 50 the latter is surfaced by means of hand-floats. With my improved structure means is provided for crowning the pavement; which is adapted to exert a pressure upon the face of the pavement during crowning, 55 so as to insure a uniform leveling throughout the entire width of the pavement. The pressure also produces a compression resulting in a harder, and therefore a better face for the pavement. However, not only have 60 I provided an apparatus for properly crowning the pavement, but I have devised a structure which—during the crowning operation—surfaces the face of the pavement by moving across the face of the pavement 65 and in sliding contact therewith, a flat surface or surfaces. In the preferred form of the invention the surfacing means is employed in conjunction with the means for leveling or crowning the pavement, though 70 I do not consider the invention limited to the employment of the leveling and surfacing means in combination.

Referring to the one embodiment of my invention shown in the drawings, A designates a frame, herein shown as composed of spaced channel members B and C. Arranged upon the frame for reciprocation longitudinally thereof are one or more surfacing members, four being shown in the drawings, viz: D, D', D² and D³. The opposite ends of the frame A rest upon supports E, the wheels F of which travel upon the curb or other suitable support such as the tracks G arranged at the side of the road or 95 the like being paved. Preferably the surfacing members have their bottom or surfacing faces formed by flat metal strips H suitably secured to the body portion I of the surfacing members. The side edges J of 100 the strips H abut so as to form a continuous surface laterally of the reciprocating members. K are a plurality of hanger frames spaced longitudinally of the frame A and having the sides L thereof secured to the 105 members B and C. Preferably the sides L are attached to the channel members so as to be vertically adjustable, the attachment being herein shown as composed of a bolt M which engages a vertical slot N in the sides 110 L. Thus by loosening the bolt M the hangers may be vertically adjusted as desired.

Each of the hangers is provided with a rod or shaft O that extends through longitudinal slots P in the reciprocating members. These slots are preferably provided with a metallic lining Q of a width to nicely receive the rollers R upon the shaft O . As shown, the body portion I of the reciprocating members is of lesser width than the plates H , and in order to hold the body portions of the reciprocating members in proper spaced relation, the portions I of the adjacent members are separated by spacers S upon the shaft O , while spacers T are arranged upon the shaft O intermediate the sides L and the members D and D' . At suitable intervals the upper edges of the body portions I are held in spaced relation by rollers a journaled upon shafts b which are carried by cross bars c that are attached to the frame. Also suitable guide rollers d are provided for the members D and D' .

While the members D to D' inclusive may be actuated as desired, I find it advantageous to reciprocate alternate members in opposite directions, since this not only effects a better surfacing, but equalizes the thrusts against the supports. Thus, the thrust caused by part of the members moving in one direction, is offset by other members moving in the opposite direction. As shown, U is a crank shaft journaled in bearings V that are attached to the sides of the frame A . W are pitmens connected to the cranks X on the shaft U , and Y are yokes attached to alternate reciprocating members and to which the outer ends of the pitmens are fastened. One of the cranks X is preferably arranged at substantially 180° in relation to the other crank and, therefore, during the rotation of the shaft U the alternate members of the series will be moved in opposite directions.

The crank shaft U may be driven in any suitable manner but I preferably arrange upon the frame A a suitable motor such as the explosion engine A' , which through the gear train B' is connected to the shaft U .

At the forward edge of the frame A is arranged an outwardly and upwardly-extending deflector C' illustrated herein as in the form of a metal strip secured to the forward edge of the strip H that is attached to the member D' . The member C' forms a deflector and prevents the plastic material C^2 from passing over the strips H .

The surface D^4 formed by the bottom faces of the abutting strips H is made of substantially the desired contour for the crown of the road, and while the proper contour of this surface may be effected in various ways, I have devised a novel arrangement of parts whereby the apparatus may be readily adjusted so as to give the surface D^4 any predetermined crown within, of course, certain limits. The variation in the crowning of

roads, however, is not very great. Thus the body portion I of each of the reciprocating members is formed of a plurality of sections connected together by adjusting devices E' , herein shown as each composed of pairs of bars F' and G' respectively connected to adjacent sections in immediate proximity to the ends thereof, and an adjusting bolt H' . One end of this bolt is provided with a head a' having oppositely-extending studs b' that pivotally engage apertures c' in the upper ends of the bars F' . The opposite threaded end of the bolt passes through an aperture in a block e' that is pivoted between the upper ends of the bars G' . The projecting end I' of the bolt is provided with adjusting nuts J' J^2 arranged upon opposite sides of the block e' and the ends of the sections abut adjacent the bottom but diverge from the bottom. Each of the strips H is connected to the body portion I by a plurality of longitudinally spaced bolts e , but as will be noted upon reference to Figs. 6 and 7, the strip H is not attached to the body portion in immediate proximity to the ends of adjacent sections but the bolts e are spaced a considerable distance therefrom. The ends of the adjacent sections of the body portion I are, therefore, free to move, to a limited extent, in relation to the portion of the strip H that passes therebeneath. Therefore, by loosening the nut J' and tightening the nut J , there will be a tendency to straighten the ends of adjacent sections, as shown in Fig. 6, while by loosening the nut J and tightening the nut J' the upper edges of the ends of adjacent sections will be spread, which will cause the strip H to curve or bow upwardly, as shown in Fig. 7. The slots P are parallel or substantially parallel with the portion of the strip H directly therebeneath so as to better guide the reciprocating members in an arc during the longitudinal movement thereof.

By the structure just described it will be readily seen that by properly adjusting the hangers K vertically and adjusting the connection between adjacent sections of the reciprocating members, the crowning surface D^4 of the apparatus may be varied to a considerable degree.

In the operation of the structure so far described, after the concrete or like material has been poured upon the road-bed in the usual manner, the wheels F of the apparatus are arranged upon the curbs and the device is suitably propelled longitudinally of the road. During the longitudinal movement of the apparatus the finishing members are reciprocated by the motor A' , since the surface D^4 is of the contour desired for the crown. As the structure is moved longitudinally over the road-bed, the proper crown will be given to the concrete or the like and also the face of the road will be surfaced by the members reciprocating thereacross. The re-

ciprocating members not only serve to finish the face of the road, but they also tend to produce a more uniform mixture at the face of the road. Preferably the surface D^4 5 slants upwardly a slight distance toward the front of the machine and is arranged at a proper height to exert a pressure upon the face of the road. During movement of the device longitudinally of the road the concrete 10 at the face of the road will be compressed, and since the surface D^4 is comparatively wide, the concrete is prevented from flowing down underneath the strips H . As before stated, preferably the surface D^4 is arranged to 15 slant slightly upward toward the front of the machine. This may be accomplished in any suitable manner as by adjusting the rear wheels upon their supports. By effecting the proper vertical adjustment of the 20 rear wheels any desired compression may be obtained. As shown, each of the wheels F is carried by arms h pivotally connected at i to a bracket j that is secured to the channel side member of the frame. The bracket j 25 is provided with a vertical series of apertures k with which the pivot h is adapted to detachably engage. Slidably engaging a slot l in the bracket is a bolt m that serves to clamp the arms h to the sides of the bracket 30 j in the different positions of adjustment of the arms. o is a bolt having a threaded engagement with a bearing p in the bracket j and serving to assist in holding the bolt m in its adjusted position. Thus by adjusting 35 the bolt o and arms, the position of the arms h may be varied as desired.

It is advantageous in transferring the apparatus from one point of the road to another, and particularly in drawing the 40 machine back over the portion of the road that has been surfaced, to provide means for raising the rear end of the surfacing members out of engagement with the face of the road. In order to permit this to be 45 readily accomplished, each of the rear wheels is journaled upon a shaft q having eccentrics r that engage bearings s in the arms h . One end of the shaft q projects beyond one of the arms, and to this projecting end t is attached a lever u . Normally the parts just described are in the position shown in full lines in Fig. 3. When it is desired to raise the apparatus the lever u is moved to the position shown in dotted lines 55 in Fig. 3.

Preferably the surfacing apparatus is propelled forwardly by the engine A' . Thus A^2 is a shaft driven from the engine crank shaft through the sprocket chain B' and 60 is provided at its outer end with a worm C^2 that engages a worm-wheel D^5 fixed to a shaft E^2 . This shaft is journaled in suitable bearings F^2 at the front of the frame A , and arranged upon the shaft E^2 adjacent opposite ends thereof are drums G^2 , 65

Extending from these drums to stakes or other anchors H^2 arranged a suitable distance in advance of the machine are cables I^2 . The worm drive will provide a suitable step-down train for propelling the machine 70 forward at a comparatively slow rate of speed. However, the speed may be varied as desired.

While I have shown and described the preferred form of my invention I do not 75 desire to limit my protection to the particular structure illustrated, but consider the invention to be of sufficient scope to embody various modifications thereof. Also my improved device may be used in connection 80 with paving other than paving for roads.

What I claim as my invention is:—

1. In a paving apparatus, the combination with a frame adapted to span a road bed, a surfacing member for use with plastic material mounted upon the frame for movement transversely of the road bed, means for adjusting the relation of said member vertically to vary its relation to the road bed, and means mounted upon the frame for actuating said member.

2. In a paving apparatus, the combination with a frame, adapted to span a road bed, of a surfacing member for use with plastic material extending transversely of the frame and having a contour conforming substantially with the finished contour of the pavement, and means mounted upon the frame for reciprocating said member transversely of the road bed.

3. In a paving apparatus, a frame, means for propelling the frame, a plurality of surfacing members arranged in close proximity to one another mounted upon the frame for reciprocation, guides for controlling the movement of said members, and means for simultaneously actuating one of said members in one direction and another of said members in the opposite direction transversely of the direction of travel of the frame.

4. In a paving apparatus, a frame, a plurality of surfacing members mounted side by side upon said frame in close proximity to one another for reciprocation, guides for controlling the movement of said members, and means for simultaneously actuating alternate members in opposite directions.

5. In a paving apparatus, a frame, a plurality of elongated parallel surfacing members arranged in close proximity to one another extending longitudinally of the frame from side to side thereof, a plurality of guides spaced longitudinally of the frame and engaging said surfacing members, and means for reciprocating the surfacing members longitudinally.

6. In a paving apparatus, a frame, a plurality of parallel surfacing members extending longitudinally of the frame, longitu-

- dinal slots in said members, means carried by the frame and extending through said slots for guiding the movement of said members, and means for reciprocating said members.
7. In a paving apparatus, a frame, a plurality of reciprocating surfacing members extending longitudinally of the frame and arranged in close proximity to one another, the surfacing faces of said members being comparatively flat and arranged to extend continuously from side to side and front to back of the frame, and means for reciprocating said members.
15. 8. In a paving apparatus, a frame, and a reciprocating surfacing member mounted upon said frame for movement and having an arched surfacing face variable in radius.
9. In a paving apparatus, a frame, and an arched surfacing member mounted upon said frame for movement, means for varying the curvature of the surfacing member, and means for guiding said surfacing member.
25. 10. In a paving apparatus, a frame, an adjustable surfacing member mounted upon said frame for reciprocatory movement, means for adjusting said member to give a predetermined crown to the surfacing face of said member, and adjustable guiding means for said surfacing member.
11. In a paving apparatus, a surfacing means, means for varying the crown of said surfacing means, means for imparting movement to said surfacing means, and adjustable means for guiding the movement of said surfacing means.
12. In a paving apparatus, a frame, a plurality of surfacing members mounted upon said frame for reciprocation, means for adjusting said surfacing members to vary the crown thereof, and means for reciprocating said members.
13. In a paving apparatus, a frame, a plurality of surfacing members arranged in close proximity to one another mounted upon said frame and means for reciprocating said members, said paving members being provided with comparatively flat faces forming a comparatively wide flat surface, and said surface having a contour substantially that desired for the crown of the pavement, said surfacing members being adapted to exert a pressure upon the face of the pavement.
14. In a paving apparatus, a plurality of elongated composite parallel members, a frame supporting the same, the components of each member being adjustable in an angular relation to each other, and a surfacing strip secured to the bottom of each composite member, and extending from end to end thereof.
15. In a paving apparatus, a plurality of elongated composite parallel members, the components being each intermediately supported and respectively tilttable endwise, means for adjusting each two adjacent components of each member in various angular relations with each other, and a surfacing strip secured to the bottom of each composite member and extending from end to end thereof.
16. In a paving apparatus, the combination with two substantially alined elongated members, of a flexible surfacing strip secured to the bottoms of said members, and means for slightly adjusting the members in various angular relations.
17. In a paving apparatus, a composite elongated member, a flexible surfacing strip secured to the bottom of said member, and means for slightly adjusting the components at their junctures in various angular relations.
18. In a paving apparatus, a plurality of elongated flexible surfacing strips, arranged to form a continuous surface, of means for longitudinally reciprocating said strips.
19. In a paving apparatus, a plurality of elongated, flexible surfacing strips arranged to form a continuous surface, means for longitudinally reciprocating said strips, the alternate strips being moved in opposite directions.
20. In a paving apparatus, the combination with a plurality of elongated, flexible surfacing strips, arranged to form a continuous surface, the strips being curved from end to end to crown said surface, of means for adjusting the strips to vary the curvature of said surface.
21. In a paving apparatus, the combination with two elongated members, substantially alined, of an adjusting screw connecting said members, permitting the same to be arranged in various angular relations, and a flexible surfacing strip secured to the bottoms of said members.
22. In a paving apparatus, the combination with two rigid elongated members substantially alined and each free to tilt about a transverse axis intermediate of its ends, of a flexible surfacing strip secured to the bottoms of said members, and an adjustable connection between the adjacent ends of the members, allowing various angular relations to be effected between them.
23. In a paving apparatus, the combination with two rigid elongated members, substantially alined, and respectively formed with intermediate longitudinal slots, of supports passing transversely through said slots, and guiding the members in a reciprocating motion, means connecting the two members, and means reciprocating the same in unison, and a flexible surfacing strip secured to the bottoms of said members.
24. In a paving apparatus, the combination with two substantially alined elongated members, of a flexible surfacing strip secured to the bottoms of said members, and means for adjusting each two adjacent components of each member in various angular relations with each other, and a surfacing strip secured to the bottom of each composite member and extending from end to end thereof.

- tion with two rigid elongated members, substantially alined, and each free to tilt about a transverse axis intermediate of its ends, of a flexible surfacing strip secured to the bottoms of said members, and an adjustable connection between the ends of the members, allowing various angular relations to exist between them, the ends of the members being free to move to a limited extent in relation to the adjacent portions of the strips.
25. In a paving apparatus, the combination with two rigid elongated members, substantially alined, and slightly adjustable in various angular relations, each member being intermediately slotted, a shaft extending horizontally through each of said slots, a roller mounted within each slot upon the correlated shaft, a frame in which the shaft extremities are mounted, means carried by the frame for reciprocating the two members in unison, and a surfacing strip secured to the bottoms of the two members.
26. In a paving apparatus, the combination with a plurality of elongated members arranged side by side, of surfacing strips secured to the bottoms of said members and forming a substantially continuous surface, spacers interposed between the members, and means for reciprocating the members, the alternate members being shifted in opposite directions.
27. In a paving apparatus, the combination with a plurality of elongated members, arranged side by side, and intermediately slotted, of surfacing strips secured to said members forming a continuous surface, a supporting and guiding member passing through said slots, a frame upon which the extremities of the supporting and guiding members are mounted, and means carried by the frame for reciprocating the elongated members.
28. In a paving apparatus, a frame, a plurality of elongated parallel surfacing members, adjustable vertically relative to the frame, means for adjusting said members to vary the crown thereof, and means carried by the frame for reciprocating the members.
29. In a paving apparatus, the combination with supporting wheels arranged at opposite ends thereof, of a surfacing section extending between the wheels, a motor mounted upon the frame, drums, a drive connection between the drums and the motor, and cables engaging the drums and adapted to extend to anchors forwardly of the machine, for the purpose described.
30. In a paving apparatus, the combination with a surfacing section adapted to extend from side to side of the roadway, wheels arranged at the sides of the roadway and carrying said surfacing section, a motor arranged adjacent one end of the surfacing section, and means for effecting a movement of the surfacing section driven from said motor.

In testimony whereof I affix my signature in presence of two witnesses.

ROBERT D. BAKER.
